UNITED STATES PATENT OFFICE.

CHARLES CUNO, OF OCONOMOWOC, WISCONSIN, ASSIGNOR TO CONNECTICUT AUTO ENGINEERING CORPORATION, OF MERIDEN, CONNECTICUT, A CORPORATION OF CONNECTICUT.

ELECTRIC-CIRCUIT CONTROLLER FOR INTERNAL-COMBUSTION ENGINES.

No. 902,522.

Specification of Letters Patent.

Patented Oct. 27, 1908.

Application filed September 19, 1906. Serial No. 335,176.

To all whom it may concern:

Be it known that I, CHARLES CUNO, a citizen of the United States, residing at Oconomowoc, in the county of Waukesha and State of Wisconsin, have invented certain new and useful Improvements in Electric-Circuit Controllers for Internal-Combustion Engines, of which the following is a specification, reference being had to the accompanying drawing, forming a part thereof.

This invention relates to improvements in circuit controllers for internal combustion engines, and more particularly to an improved timer, so-called, whereby the primary circuit of an induction coil apparatus employed for ignition systems is opened and closed at the proper time.

The main object of the invention is to improve the construction, whereby the parts of the timer are easily and effectively assembled and adjusted, said construction being very reliable and effective.

In the accompanying drawings, Figure 1 is a front elevation of my invention; Fig. 2 is, in the main, a cross section on the plane of the line $x-x$ of Fig. 1.

In that particular form of my invention shown in the drawings, the timer, so-called, is adapted to control a circuit leading to four primary coils (not shown), although the number of coils employed is immaterial.

1 is a ring of insulating material, carrying blocks 2-2, which are insulated from each other and connected respectively with binding posts 3-3. These binding posts are carried by the ring 1 or a covering 4, which, if of conducting material, should be insulated from the binding posts 3, as by insulating washers 5-5. The covering 4 may constitute a part of an inclosing case, including the back 4^a and the hub 4^b, and the removable cover 4^c detachably mounted and held to the back 4^a in any suitable manner, as by screw-bolts 4^d and thumb-nuts 4^e. The cover 4^c has the hub portion 4^f.

6 is an end adjusting nut adapted to the hub 4^f.

7 is an anti-friction bearing carried within the hub 4^b.

7^a is another anti-friction bearing carried within a recess in the hub 4^f. The inner end of the adjusting nut 6 bears against one of these anti-friction bearings, for example 7^a.

8 is a shaft passing through the case and

rotatably mounted in the bearings 7-7^a on opposite sides of the case.

9 is a hub or sleeve connected upon the shaft 8 and having the extension 9^a on one side and the extension 9^b on the opposite 60 side.

10 is a lever pivotally mounted intermediate its length upon the extension 9^a. One end of this lever 10 carries a contact roll 11, while the other end is connected by a spring 12 to the arm 9^b. The effect of the spring 12 is to force the roll 11 outwardly into contact with the inner wall of the ring 1 and the contact blocks 2-2. This contact roll 11 is preferably beveled at its periphery, 70 and each of the blocks 2-2 is correspondingly beveled to receive the same so as to produce rubbing action between the two parts when they meet. The insulating ring 1 is preferably slightly grooved, as indicated in dotted lines Fig. 1, to receive the extreme edge of the periphery of the contact roll 11.

The shaft 8 may be secured in any desired manner to the driving shaft 14, which, in an ordinary four-cycle engine, rotates in time with the cam shaft (not shown).

As will now be seen, the case carrying the contact blocks 2 is supported at opposite sides upon the shaft 8. These bearings are located respectively on opposite sides of the hub 9 and the associated parts, with the result that the strain occasioned by the spring 12 is balanced. End-play may be prevented by setting up on the adjusting nut 6, this in turn coöoperating with the anti-friction bearings in any suitable manner. When the desired adjustment is secured, the nut 6 may be locked in place in any well-known manner, for example, by a screw 6^a passing through the flange on the head of the nut and engaging with the hub 4^f. By this means the case is mounted to rotate in a most effective manner, end-play and wobbling, due to wear, being entirely eliminated. 100 The anti-friction bearings in this instance being ball-bearings, may be provided with the usual ball races or retainers, well known in the art, and to which I lay no claim of novelty. The binding posts 3 may be constructed in any well-known manner, the particular form shown herein being made the subject-matter of another application, divided from this case. The timer shifter (not shown) by which the angular position 110

of the instrument is changed may be connected in any suitable manner, as by means of an extension from one of the bolts 4^a.

I claim:

5. 1. In a device of the character described, a shaft, a contact arm carried thereby, a case including a removable part, bearings between the case and said shaft and arranged on opposite sides of the contact device, contact blocks carried by but insulated from said case and arranged in the path of the contact device, external terminals for said blocks and an adjusting device for said bearings, said adjusting device being carried by 15 said removable part of said case.
  2. In a device of the character described, a shaft, a contact arm carried thereby, a contact carried by said arm, means for forcing said contact outwardly, a case surrounding said shaft, arm and contact, part of said case being removable, bearings between said case and said shaft and arranged on opposite sides of the contact arm to balance the strain thereof, insulated contact blocks carried by said case and arranged in the path of the contact device, external terminals for said blocks and means external to said case for adjusting said bearings.
  3. In a device of the character described, 30 a case, a contact block carried thereby, a shaft supporting said case, a contact device carried by said shaft and arranged to traverse said block, bearings between said shaft and case on opposite sides of the contact device, carried by the shaft, and means for adjusting said bearings accessible from the outer side of the case.
  4. In a device of the character described,
- a shaft, a case supported thereby, antifriction bearings between said shaft and said case, a contact arm carried by said shaft between said bearings, an insulated contact block carried by the case in the path of movement of said contact carried by the shaft and means external to the case for adjusting said bearings. 40
5. In a device of the character described, a shaft, a case supported thereby, antifriction bearings between said shaft and said case, a contact arm carried by said shaft between said bearings, an insulated contact block carried by the case in the path of movement of said contact carried by the shaft, and an adjusting device carried by the outer side of the case and arranged to 45 relatively connect with said bearings for adjustment. 50
6. In a timer or circuit breaker, a rotatable shaft, a contact device carried thereby and means for pressing the same outwardly 55 relatively thereto, a case mounted on said shaft and inclosing said contact, a contact block carried by said case in the path of movement of said contact on the shaft, antifriction bearings carried by said case and 60 arranged between said case and said shaft and on opposite sides of the contact device carried thereby, and a device adjustably carried by said case and coöperating with said antifriction bearings for adjustment. 65
- 70 In witness whereof I hereto affix my signature in presence of two witnesses.
- CHARLES CUNO.
